(57) **CLAIM**

The ornamental design for a large droplet twin spray nozzle, as shown and described.

DESCRIPTION

FIG. 1 is a perspective view taken from the front, bottom, and right side of the ornamental design for a large droplet twin spray nozzle.

FIG. 2 is a perspective view taken from the front, top and right side of the large droplet twin spray nozzle of FIG. 1. FIG. 3 is a front elevation view of the large droplet twin spray nozzle of FIG. 1.

FIG. 4 is a rear elevation view of the large droplet twin spray nozzle of FIG. 1.

FIG. 5 is a right side elevation view of the large droplet twin spray nozzle of FIG. 1.

FIG. 6 is a left side elevation view of the large droplet twin spray nozzle of FIG. 1.

FIG. 7 is a bottom plan view of the large droplet twin spray nozzle of FIG. 1; and,

FIG. 8 is a top plan view of the large droplet twin spray nozzle of FIG. 1.
